JAMES L. HAVEN, OF CINCINNATI, OHIO.

Letters Patent No. 85,819, dated January 12, 1869.

IMPROVEMENT IN GRINDSTONE-JOURNAL BOXES.

The Schedule referred to in these Letters Patent and making part of the same.

To whom it may concern:

Be it known that I, JAMES L. HAVEN, of Cincinnati, Hamilton county, Ohio, have invented a new and useful Grindstone-Journal Box; and do hereby declare the following to be a full, clear, and exact description thereof, reference being had to the accompanying drawings, making part of this specification.

My invention consists in constructing the boxes or housing for grindstone-journals in such a manner as to secure the friction-rollers against displacement, and to protect their bearings from the water and grit which are continually projected from the stone when it is in operation.

Figure 1 is a perspective view of a grindstone-journal box, embodying my improvements.

Figure 2 is a transverse section in the line $x-x$.

Figure 3 is a perspective view, showing a modification of my improvement with the cap removed.

Figure 4 is a partially-sectioned plan, showing a modification of the friction-rollers.

The housing or box proper consists of a single casting, A, whose perforated bosses, I, afford journal-bearings for the shafts $e e'$ of the friction-rollers C C', which journals are cast solidly to their respective rollers, and permanently, although loosely, within said bosses, so as, while permitting free rotation of said rollers, to make them irremovable from their housing.

The upper portions of the bosses I project beyond the ends of the shafts $e e'$ sufficiently to protect them from any dirt, grit, or moisture.

The box A has lugs, D D', perforated to receive screws G G', which serve to attach to the frame, not only said box, but a cover, B, provided with similar

luggs, E E', and which are likewise traversed by the screws G G'.

The box A and the cover B serve in conjunction to protect the rollers from sand, water, and other impurities.

It will be seen that this journal-box, with its pair of rollers complete, is composed of four simple and easily-moulded castings.

Fig. 3 shows a modification of my improvement, in which the box proper is composed of two castings, A A', held together by means of flanges, b b, fig. 2, on the cap, or by means of bolts or rivets, which extend through the holes a a in fig. 3, thus composing the sides of the box.

In fig. 4 still another modification is seen, in which the rollers rotate upon fixed axles, which are riveted to the box, thus answering the purposes of the bolts or rivets required in fig. 3, or the flanges required on the cover, as in fig. 2.

I claim herein as new, and of my invention—

1. The box or housing A A, cast in two pieces and connected together by rivets or other means, as represented in the drawings, figs. 1, 2, 3, 4.

2. The grindstone-journal box, composed of the box A and the cover B, united in the manner set forth, and containing the rollers C C' permanently fixed therein, as described.

In testimony of which invention, I hereunto set my hand.

JAMES L. HAVEN.
